(57) **CLAIM**

The ornamental design for a light emitting diode lamp, as shown and described.

DESCRIPTION

FIG. 1 is a perspective view of a light emitting diode lamp showing the new design;

FIG. 2 is a front view thereof;

FIG. 3 is a rear view thereof;

FIG. 4 is a right side view thereof, the left side view being a mirror image thereof;

FIG. 5 is a top view thereof, the bottom view being a mirror image thereof;

FIG. 6 is a cross-sectional view taken along line 6—6 in FIG. 2 with the internal parts omitted, wherein the portions having the double slanted lines are transparent;

FIG. 7 is a cross-sectional view taken along line 7—7 in FIG. 2 with the internal parts omitted, wherein the portions having the double slanted lines are transparent; and,

FIG. 8 is an enlarged partial view taken along lines 8—8 in FIG. 8 with the internal parts omitted, wherein the portions having the double slanted lines are transparent.

CERTIFICATE OF CORRECTION

PATENT NO. : Des. 578,699 S
APPLICATION NO. : 29/297412
DATED : October 14, 2008
INVENTOR(S) : Hajime Ohno et al.

Page 1 of 1

It is certified that error appears in the above-identified patent and that said Letters Patent is hereby corrected as shown below:

On the Title page of the patent grant, please replace the last paragraph of the Description from
“FIG. 8 is an enlarged partial view taken along lines 8-8 in FIG. 8 with the internal parts omitted,
wherein the portions having the double slanted lines are transparent.” to -- FIG. 8 is an enlarged partial
view taken along lines 8-8 in FIG. 7 with the internal parts omitted, wherein the portions having the
double slanted lines are transparent. --

Signed and Sealed this

Fifth Day of January, 2010

David J. Kappos
Director of the United States Patent and Trademark Office
